UNITED STATES PATENT OFFICE.

ANTHONY PAPINI, OF SOUTH BETHLEHEM, PENNSYLVANIA, ASSIGNOR OF FORTY
ONE-HUNDREDTHS TO EDMUND LIEDKE, OF ALLENTOWN, PENNSYLVANIA.

GAS-BURNER AND VALVE-ACTUATING MECHANISM.

1,142,454.

Specification of Letters Patent.

Patented June 8, 1915.

Application filed May 15, 1914. Serial No. 838,849.

To all whom it may concern:

Be it known that I, ANTHONY PAPINI, a subject of the King of Italy, residing at South Bethlehem, in the county of Northampton and State of Pennsylvania, have invented certain new and useful Improvements in Gas-Burner and Valve-Actuating Mechanism, of which the following is a specification.

10 This invention relates to a gas burner and valve actuating mechanism and the principal object of the invention is to provide improved means for holding the valve open and permitting the valve to be closed 15 in case the gas becomes extinguished after being lighted.

Another object of the invention is to provide means for releasably holding the valve open and permit the valve to be held open 20 the desired amount.

Another object of the invention is to so construct the automatic actuating mechanism that the valve will not be operated when the gas is lighted but will be actuated 25 if the gas becomes extinguished.

This invention is illustrated in the accompanying drawings, wherein—

Figure 1 is a longitudinal sectional view showing the valve open; Fig. 2 is a fragmentary view shown principally in top plan and partially in section; Fig. 3 is a fragmentary vertical sectional view of the actuating mechanism; Fig. 4 is a fragmentary view in top plan of the expanding bar and 30 its support; Fig. 5 is a fragmentary view of the actuating mechanism; and Fig. 6 is a sectional view taken along the line 5—5 of Fig. 1.

The expanding and contracting bar 10 is 40 pivotally supported at one end by the standards 11 and extends across the burner 12 so that when the gas is lighted the heat from the lighted gas will expand the bar 10 and move the link 13 to rock the pawl 14. 45 This pawl 14 is pivotally mounted between the supporting plates 15 upon bolt 16. The lower end portion of this pawl is formed into a tooth 17 which engages the teeth of the rack plates 18 which are in their turn 50 pivotally connected with the sliding pawl 19 by means of the bolt 20. The free end portions of the rack plates 18 are formed into leaf springs 21 which engage the base plate 22 and yieldably hold the plates in the 55 normal position shown in Fig. 1. The

springs 23 have their upper ends connected with the pin 24 and have their free ends engaging the pin 20 to yieldably hold the pawl 19 in its normal position. When this pawl 19 is in its normal position the ends 60 of pin 25 will move up the inclined cam blocks 26 to raise the plates 18. These cam blocks 26 also form a function which will be brought out farther on. The valve 27 communicates with the feed pipe 28 of 65 burner 12 and is provided with a stem 29 which is normally held in a position to close the valve by means of the spiral spring 30. A ratchet plate 31 is carried by the valve stem 29 beneath the handle 32 and is 70 engaged by the pawl 19 so that when the valve stem is turned to an open position the pawl by engaging the teeth of the plate 31 will releasably hold the valve in an open position. An actuating lever 33 is pivotally 75 connected with the valve stem above the plate 31 and is yieldably held in spaced relation to the handle 32 by means of the spring 34. This lever 33 is provided with a finger 35 which extends between the upper 80 and lower plates of the curved head 36 which is carried by the U-shaped lever 37. This lever 37 is pivotally mounted upon the bolt 38 and has its inner arm 39 extending to engage the plates 18 when the outer 85 end portion of the lever is swung upwardly by means of lever 33.

When it is desired to light the gas the handle 32 and lever are grasped and the lever 33 pressed toward the handle 32. This 90 raises the finger 35 and rocks the lever 37 to move the arm 39 downwardly into engagement with the plates 18. When the plates 18 are engaged by the arm 39 they are pressed downwardly and as the pin 25 engages the 95 cam blocks 26 the plates will be moved to draw pawl 19 inwardly out of engagement with the rack plate 31. The valve stem can then be turned upon the valve the desired amount and the lever 33 then released. 100 When this lever 33 is released springs 23 will move pawl 19 outwardly into engagement with rack plate 31 thus engaging the plate and releasably holding the valve stem in the open position. When the gas is 105 lighted the heat will cause bar 10 to expand thus moving the pawl into engagement with the teeth of plates 18. It should be noted that the teeth of the plates and the tooth 17 of pawl 19 are cut at such an angle that the 110

pawl will easily ride over the teeth of plates 18 while bar 10 is expanded. If the gas becomes extinguished by any cause the bar 10 will cool and contract thus drawing pawl 13. 5 When the pawl is moved in this direction the tooth 17 cannot move out of engagement with the teeth of plates 18 and therefore plates 18 will move with the pawl and draw pawl 19 to a position to release rack plate 10 31 and permit the valve stem 29 to be turned to a closed position by spring 30. It is of course obvious that if it is desired to turn the gas off by hand the lever 33 may be pressed to rock lever 37 and move plates 18 15 inwardly. This action will lower the plates out of engagement with pawl 14 and draw pawl 19 inwardly out of engagement with rack plate 31 thus permitting the valve stem to be moved to a closed position. I have 20 therefore provided a device for automatically permitting the valve to be closed in case the gas becomes extinguished, the valve actuating mechanism being so constructed that it may be manually operated as well as 25 automatically.

What is claimed is:—

1. In a device of the character described, a burner, a valve for said burner, a valve stem for said valve having its upper end 30 portion provided with a handle, a rack plate carried by said valve stem, resilient means normally holding said valve stem in a closed position, a lever pivotally connected with said valve stem and having its inner end 35 portion provided with a finger, a pivotally mounted U-shaped lever having one arm provided with a slotted head, said finger extending into the slot of said head to permit said U-shaped lever to be moved by said first 40 mentioned lever, a slidably mounted pawl yieldably held in engagement with said rack plate, a rack plate pivotally connected with said pawl and having its free end portion formed into a spring for yieldably holding 45 said second rack plate in a normal position, a cam engaging said second rack plate, a pivotally mounted pawl having its free end

portion engaging said second rack plate, and an expansion and contraction plate extending across said burner and connected 50 with said pivotally mounted pawl.

2. In a device of the character described, a burner, a valve, a stem for said valve yieldably held in a closed position, a rack carried by said valve stem, a pawl yieldably 55 held in a position to engage said rack and releasably hold said stem in an open position, a slidably and pivotally mounted rack carried by said pawl, manually operated means for engaging said second rack to 60 move said pawl to a position to release said first mentioned rack, a pawl engaging said second rack, and means effected by heat and cold for operating said second pawl to move 65 said second rack to a position to move said first mentioned pawl to release said first mentioned rack.

3. In a device of the character described a burner, a valve for said burner, a stem for 70 said valve yieldably held in a closed position and having one end portion provided with a handle, a rack carried by said valve stem, an actuating lever pivotally connected with said valve stem and having one end portion provided with a finger, a pivotally 75 mounted U-shaped lever having one arm provided with a slotted head to receive said finger and permit said U-shaped lever to be moved by said first mentioned lever, a slidably mounted pawl yieldably held in engagement with said rack plate, and a rack pivotally connected with said pawl and constituting a spring element and positioned for engagement by said U-shaped lever when said U-shaped lever is moved out of its 80 normal position by said first mentioned lever.

In testimony whereof I affix my signature in presence of two witnesses.

ANTHONY PAPINI.
